UNITED STATES PATENT OFFICE.

GEORGE H. RENNICK, OF INDIANAPOLIS, INDIANA.

DESIGN FOR AN EMBLEM-BUTTON.

55,398.

Specification for Design.

Patented June 1, 1920.

Application filed February 19, 1920. Serial No. 359,959. Term of patent 14 years.

To all whom it may concern:

Be it known that I, GEORGE H. RENNICK, a citizen of the United States, residing at Meridian Life Building, in the city of Indianapolis, county of Marion, State of Indiana, have invented a new, original, and ornamental Design for Emblem-Buttons, of which the following is a specification, reference being had to the accompanying drawing, forming part thereof.

The figure is a plan view of an emblem button, showing my new design.

I claim:

The ornamental design for an emblem button, as shown.

GEORGE H. RENNICK.

Witnesses:

W. E. BASSON,
H. C. FREDERICKS.
